COIN CONTROLLED MECHANISM FOR VENDING MACHINES

Original Filed April 8, 1924 2 Sheets-Sheet 2

UNITED STATES PATENT OFFICE.

JOHN R. NOLAN, OF NEW YORK, N. Y.

COIN-CONTROLLED MECHANISM FOR VENDING MACHINES.

Original application filed April 8, 1924, Serial No. 704,922. Divided and this application filed April 23, 1925, Serial No. 25,215. Renewed November 2, 1927.

This invention relates to coin-controlled operating devices for the article delivering element of a vending machine, such, for example, as illustrated in my co-pending application Serial No. 704,922, filed April 8, 1924, of which the present application is a division.

The main object of the invention is to provide simple, inexpensive and durable mechanism manually operable, with ease and certainty, to actuate the article delivery element when and only when a proper coin is supplied to the mechanism. Other objects of the invention will hereinafter appear.

15 The invention, in the preferred form illustrated, is associated with a rotary article-delivery device, and comprises a manually operative rotary coin-receiving member and novel locking and releasing devices therefor, 20 including a ratchet wheel operatively connected with the delivery device. The coin receiving member is resiliently connected with the ratchet wheel to permit limited relative movement therebetween. A pawl member 25 normally in interlocking engagement with the wheel prevents abnormal forward, as well as retrograde movement of the wheel. This pawl is releasable from the wheel by the opposing action of a projecting coin in said member when the latter is 30 initially rotated, thus permitting the continued manual rotation of the coin-receiving member and the ratchet wheel to effect the discharging operation of the delivery device.

35 The invention also comprises a novel construction and arrangement of the coin chute in relation to the coin-receiving member; a novel arrangement of the locking and releasing devices in relation to a rotary article 40 delivery device, and other features of construction and combinations of parts which will be hereinafter described and claimed.

In the drawings—

Figure 1 is a transverse vertical section of 45 a vending machine embodying the features of my invention.

Fig. 2 is a similar section through the rotary delivery device, and adjuncts, showing the device as partly turned to engage 50 the lowermost article contained in the magazine.

Fig. 3 is a similar view, showing the deliv-

ery device farther advanced and illustrating its ejecting action.

Fig. 4 is a perspective view of the delivery 55 device, its shaft and the ratchet wheel.

Fig. 5 is a similar view of the associated coin receiving disk and coin chute as removed from the ratchet wheel, showing the turning knob, in section, as detached.

Fig. 6 is a similar view of the locking and releasing pawl.

Fig. 7 is a view of the coin disk and ratchet wheel, together with the locking and releasing pawl for the latter, showing the 65 relation of the parts the instant the pawl is disengaged from the wheel by the action of the coin in the disk, and indicating, by dotted lines, the position of the shouldered portions of the delivery device.

Fig. 8 is a similar view looking at the opposite side of the coin disk and ratchet wheel, showing the ratchet wheel as released and as initially advanced by the spring.

Fig. 9 is a horizontal section through the 75 associated coin disk and ratchet wheel, and their adjuncts.

Referring to the drawings, 12 designates a suitable casing, 26 an article-containing magazine therein, and 34 a delivery device 80 mounted beneath the magazine so as to support the contents of the latter. The form of delivery device herein illustrated is a rotary element fast on a shaft 33 mounted in the lower portion of the casing. This 85 element comprises a cylindrical body having peripheral flat portions 35 extending transversely thereof, and also circumferential projections 37 presenting impelling shoulders 38 each of which is adapted to engage 90 an article, such as a match book 39, seated on the adjacent flat portion, when the delivery device is properly rotated. Each projection extends from the shoulder through an eccentric arc which merges with the periphery of the cylindrical body, thus providing a circumferential wedge-like rib that trails the adjacent flat portion of the device 95 when it is turned clockwise.

The lower edge of the back of the magazine terminates somewhat above the periphery of the delivery device to afford an opening deeper than the greatest width of the article to be yanked, which edge is provided

with a series of independently movable fingers 39 that are so disposed as to flank the paths of the respective projections 37 and extend to or near to the peripheral path of 5 the delivery device.

When the position of the delivery device is such that the contents of the magazine rest upon or near the upper flat surface of the device, the fingers 39 bar the discharge 10 opening, and thus prevent the accidental escape therethrough of the lowermost article, but when the device is turned in a clockwise direction, the upper impelling shoulder 38 thereof bears against the opposing article 15 and forces it rearwardly and against the fingers, which fingers by their elasticity initially press the article against the shoulder. As such article is being forcibly advanced by the shoulder, the fingers are 20 swung outwardly and are caused to ride yieldingly upon the top of the advancing article in a manner to maintain it seated squarely upon the flat surface of the delivery device until the article is discharged from. 25 the magazine. Thereupon the fingers, resuming their normal position, prevent the escape of each succeeding article from the magazine until such time as the latter shall be engaged and acted upon by the next following impelling shoulder.

A guide plate 41 is spaced slightly from the rear of the spring-guarded discharge opening of the magazine and is curved downwardly and forwardly to the bottom of the 35 delivery opening 19 in the door of the casing. This plate is so disposed in relation to the path of the delivery device that when an article is ejected from the magazine the article encounters the opposing curved surface of 40 the plate and is deflected downward thereby until it escapes from the action of the impelling shoulder, whereupon such article falls upon the lower part of the plate and is directed forwardly thereby to and through 45 the discharge opening.

In the present instance one end of the shaft 33 of the delivery device is rotatably mounted in a sleeve or hub 43 having a stud 33' which is journaled in and projects outwardly of one of the other side walls of the casing. The outer end of the stud 33' is equipped with a suitable knob or handle 44, and the inner end of the hub has formed on or fixed thereto a disk 45 having two diametrically opposite peripheral recesses 46 which are each shaped to receive the greater portion of a coin. Fast on the shaft 33, in close proximity to the face of the coin disk 45, is a ratchet wheel 47 which provides a 50 side wall for the respective coin receiving recesses. The disk and wheel are independently rotatable within limits relatively to each other, and to this end the ratchet wheel is preferably provided with an arcuate slot 48 through which extends a stud 49 from

the coin disk; and a spring 50, which is secured to the stud and to the ratchet wheel, maintains the disk and wheel normally in a position with the stud at the trailing end of the slot. The tension of the spring connection between the coin disk and the ratchet wheel is such that during the clockwise rotation of the knob 44 the spring permits an initial advance movement of the coin disk, whereupon the stud 49 bears firmly against 75 the end of the arcuate slot of the ratchet wheel and ensures a positive impelling action between the disk and ratchet members. When the turning force on the knob is released the spring returns the coin disk to its 80 normal or retracted position in relation to the ratchet wheel.

A coin chute 51 is suitably supported within the casing so as to overhang the coin disk, the upper end of the chute being formed and 85 arranged to register with a coin slot 20 in the closed door of the magazine. The outer or right hand wall of the chute is extended downwardly in close relation to the adjacent side of the coin disk, the free end of 90 the leg 51' thus formed being bifurcated to embrace a circumferential groove in the hub 43 and prevents lateral displacement of the chute relative to the coin disk. The chute leg thus being maintained in close parallel 95 relation to the coin disk affords an efficient side wall for each recess of the disk when a recess is in its upper position directly beneath the throat of the chute. Hence the upper recess, with its embracing side walls, 100 constitutes a socket into which a coin, when entered in the coin slot of the door, is directed by the chute. The lower rearward edge of the chute is cut away, as at 52, to permit the free passage of the up-projecting portion of the coin when the coin disk is partially rotated by proper manipulation 105 of the knob 44.

The ratchet wheel is not only provided with inclined back-stop teeth 53, but also with 110 two diametrically opposite peripheral spaces 54 one adjacent each socket and in such relation thereto that when an impelling shoulder of the delivery device is located adjacent its article-engaging position, i. e., forward of 115 the magazine, the upper socket is in substantial vertical alignment with the throat of the chute. The ends of each space 54 provide oppositely-disposed stops 55, 56, respectively. Pivoted on a stud 57 supported on the adjacent wall of the casing, (or other fixture) is a pawl arm 58 which extends rearwardly and lies laterally of the position of the upper coin socket. This arm is provided near its pivotal end, forwardly of the proximate coin socket, with an inwardly extending stop stud 59 that drops normally into a peripheral space 54 when the latter is positioned beneath the stud, the stops 55, 56 at the respective ends of the space thus 120 125 130

preventing forward or backward movement of the delivery device. The pawl arm is also provided, adjacent the rear open edge of the chute, with an inwardly extending 5 trip stud 60 which overhangs but does not engage the coin disk, and which stud crosses the rearward path of the upper portion of a coin contained in the upper socket.

By the mechanism just described it will 10 be seen that when the delivery device is turned in a clockwise direction by the manipulation of the knob 44, the stud 59 rides on the ratchet teeth until the leading space 54 passes beneath the stud, whereupon 15 the latter drops into such space and is engaged by the opposing stop 55, which stop positively checks the continued rotation of the delivery device, the upper socket of the coin disk then being directly beneath the throat 20 of the coin chute. Thereupon, as the knob is turned, the coin disk is independently advanced within the limits of the slot 48 of the ratchet wheel and against the action of the spring 50. If the knob now be released 25 the spring will retract the coin disk to position the upper coin socket thereof beneath the coin chute, so that if a coin be inserted in the coin slot 20 such coin will drop directly into the socket. Thereupon the act of 30 turning the knob will again move the coin disk against the action of the spring and press the coin against and under the trip stud 60, thereby raising the stud, together with the pawl arm, in a manner to lift the 35 stop stud above and clear of the stop 55 of the ratchet wheel. The instant the ratchet wheel is thus released the tensioned spring slightly advances the wheel and the delivery 40 device, thereby causing the proximate stop 55 to pass beyond the overhanging stop stud 59 of the pawl arm, and as the manual rotation of the knob is continued the coin is carried beyond the trip stud 60 and discharged from the socket. As the coin passes 45 below and beyond the trip stud the pawl arm drops by gravity (being preferably provided with a weight 61 or its equivalent), the stop-stud 59 thus riding on the periphery of the ratchet wheel. Continuing the manual 50 movement of the knob, the delivery device is turned sufficiently to effect the discharge of the lowermost article from the magazine by the impingement thereagainst of the impelling shoulder of the said device, 55 as previously described. During the ejecting action, owing to the counter-acting force incident thereto, the coin-disk is independently advanced within the limits of the slot 48 of the ratchet wheel and against the action 60 of the spring 50, the stud 40 thus bearing firmly against the opposing end of the slot. When the article has been discharged and the knob released the spring 50 retracts the coin disk to its normal position 65 relatively to the ratchet wheel.

In the continued rotation of the delivery device, after the coin has passed the trip stud of the pawl arm, the stop-stud 59 rides idly upon the toothed periphery of the ratchet disk, but if an attempt be made to 70 turn the device backward the stud 59 will at once engage a back-stop tooth 53 adjacent thereto and prevent the retrograde movement. Immediately after the coin has passed the trip stud, as previously mentioned, the coin escapes from the socket and drops into the coin compartment. The flat surfaces of the delivery device are so arranged in cooperative relation to the associated ratchet wheel and coin disk, that the 80 coin is discharged from the coin socket just at or immediately before the engagement of the impelling shoulder of the device with the opposing article in the magazine. 85

When the delivery device has been rotated a sufficient distance to position the second coin socket at the top, the stop stud 59 of the pawl arm, resuming its original position, enters the second space 54 of the ratchet wheel and co-operates with the end stops of 90 such space to prevent a succeeding operative rotation of the delivery device unless and until a coin be introduced into the now upper coin socket. If at any time the coin disk and delivery device should not be rotated sufficiently to present the upper coin socket to the coin chute after an article has been ejected, a coin subsequently introduced into the chute will nevertheless enter the 95 socket when the latter is properly positioned 100 during the succeeding rotation of the coin disk.

I claim—

1. In a vending machine, the combination of a delivery device, a rotary operating element including a coin receiving member, a ratchet wheel connected with the said device laterally of the coin member, a pawl engaging the ratchet wheel and having a trip member overhanging the coin member, 105 a connection between the coin member and the ratchet wheel whereby the coin member is capable of limited rotary movement relatively to the ratchet wheel, said connection including resilient means for maintaining the coin member normally retracted in respect to the ratchet wheel, means for directing a coin to the path of the coin receiving member and inter-engaging means between the coin receiving member and the coin 110 directing means for preventing lateral displacement of the one relative to the other. 115

2. In coin-controlled mechanism for vending machines, a rotary operating element including a peripherally socketed coin disk having a hub portion with a circumferential groove therein adjacent one face of the disk, a ratchet wheel at the other face of the disk, a connection between the coin disk 120 and the ratchet wheel whereby the coin disk 125 and the ratchet wheel whereby the coin disk 130

is capable of limited rotary movement relatively to the ratchet wheel, said connection including resilient means for maintaining the coin disk in a normally retracted position, and a coin chute leading to the periphery of the coin disk and having a leg depending adjacent the side of the coin disk opposite to the ratchet wheel and registering with the groove of the hub.

10 3. In a coin-controlled mechanism for vending machines, a rotary operating ele-

ment including a socketed coin receiver, a coin chute leading to the coin receiver, and inter-engaging means between the coin receiver and the coin chute for preventing lateral displacement of the one relative to the other.

Signed at New York in the county and State of New York this 22d day of April A. D. 1925.

JOHN R. NOLAN.
